UNITED STATES PATENT OFFICE.

WILLIAM DUBILIER, OF NEW YORK, N. Y., ASSIGNOR TO DUBILIER CONDENSER AND RADIO CORPORATION, A CORPORATION OF DELAWARE.

ELECTRICAL CONDENSER.

Application filed January 31, 1924. Serial No. 689,756.

To all whom it may concern:

Be it known that I, WILLIAM DUBILIER, citizen of the United States, residing at New York, in the county of New York and State of New York, have invented certain new and useful Improvements in Electrical Condensers, of which the following is a specification.

This invention relates to an improvement 10 in electrical condensers such as are adapted for use in radio apparatus and other electrical devices.

An object of my invention is to provide a condenser that can be manufactured in advantageous form and to the size required, and so constructed that all liability of breakage and derangement of structure or function is entirely obviated.

A further object of the invention is to 20 provide a condenser, the elements of which are arranged to be as compact as possible, and which has an outer casing or envelope that entirely encloses the body of the condenser, thereby greatly adding to the 25 strength and durability, and at the same time permitting the condenser to be easily and conveniently connected in the circuit of which it is intended to be a part. Preferably, I make the enclosing casing of metal, 30 but of course other suitable material may be used.

These and other objects and advantages of my invention are suggested or set forth in the following description; the drawings accompanying the description illustrating the best form of my invention now known to me, and the novel features are defined in the appended claims; but of course this description is explanatory only, and I may 40 vary the shape, size and arrangement of the various parts of the structure actually shown herein, without departing from the nature and scope of the invention as the same is defined by the broad and general meanings 45 of the terms in which the claims are expressed.

On the drawings, Fig. 1 is a side view of a condenser according to my invention, with its enclosing casing thereon, seen from the 50 top in Figure 2.

Fig. 2 is a top view thereof.

Fig. 3 is an end view.

Figs. 4 and 5 are views showing blanks to make the sections of which the envelope or casing of the condenser is constituted, these two sections being presented by Figs. 4 and 5 in the relative positions which they occupy when about to be applied to the body of the condenser and secured in place, these two views being on a reduced scale.

The same numerals identify the same parts throughout.

In the particular description of the preferred form of my condenser herein illustrated, I use the number 1 to indicate the body or so-called "stack" of the condenser, which consists of a top and bottom plate or sheet of insulation, between which are sheets of conductive material such as metal foil, and sheets of dielectric material such as mica, arranged in alternation so that the mica separates the foil; one-half of the sheets of foil constituting one group or set of plates for connection to one terminal of an electric circuit, and the other half of the conductive sheets constituting a complementary set of elements for connection to the opposite terminal of the circuit. The structure and arrangement of the parts of the stack 1 may be of any suitable character and is not a part of the invention herein set forth. The body or stack 1, when completed, is covered by an envelope or casing 2, which engages all of the corners of the condenser and the edges also over substantially their entire lengths, gripping the opposite faces of the condenser and keeping the conductive and dielectric sheets pressed together in firm engagement over their entire area to the extent required.

The casing or envelope 2 includes a pair of sections or members which are indicated by the reference characters 3^a and 3^b, the former being shown in Fig. 4 and the latter in Fig. 5. For convenience, the other views present the condenser with the section 3^a lying upon the face of the stack 1 which is shown as the upper face, and the section 3^b is associated with the opposite face. The section 3^a comprises a body 4^a, with one end 5^a thereof having the corners rounded and having a projection 6^a extending outward in central position with respect to this end. At the opposite extremity, this section has a

recess 7^a, and when this section is to be attached to the body of the condenser 1, the end 5^a will be bent along the two transverse lines indicated at 8^a. Likewise, the projection 6^a is intended to be bent along the three transverse lines indicated by the number 9^a, in a manner which will be more fully explained presently. At the opposite extremity, and flanking the recess 7^a, are projections 10^a, adapted to be bent along transverse lines 11^a. At each side of the blank or section 3^a are extensions 12^a, adapted to be bent along the two longitudinal lines 13^a, and one corner of these extremities 12^a is rounded as shown at 14^a. The projection 6^a has a perforation 15^a in the outer extremity of same.

The shape of the other blank or section is the same, and the various parts thereof are provided with corresponding numerals, but the letter "b" is used in connection with each numeral so that this blank, and its parts, may be distinguished throughout from the blank just described.

To attach these two blanks to the stack 1 so as to make them hold together and enclose the stack, the stack can be first laid upon the blank 3^b as indicated by the broken lines 1. The opposite ends of the condenser stack will about coincide with the lines 11^b and the inner line 8^b, and the top and bottom edges will about coincide with the inner longitudinal lines 13^b. The projections 10^b from the lines 11^b outward are at least as long as the thickness of the stack, and these projections 10^b are bent up against the adjacent end of the condenser at the opposite corners thereof. Also, the extensions 12^b are bent up against the upper and lower edges of the condenser stack adjacent the same corners, and then bent over along the outer lines 13^b down across the top face of the condenser, so that the portions of the extensions 12^b which engage the top face of the stack 1 will be close to the edges of the projections 10^b, and the corners of the condenser already mentioned will thus be firmly gripped. At the opposite extremity of the condenser, the end 5^b will be turned up first along the inner line 8^b against the end of the condenser, and then down along the other line 8^b upon the top of the stack, to grip the adjacent end of the stack over nearly the entire length of this end except at the corners. The projection 6^b is first bent about the inner line 9^b, down against the terminal portion of the end 5^b, and then again over upon the extremity of the condenser and then again outward in line with the condenser, so that a screw and nut can be employed in connection with the aperture 15^b to secure a line wire or conductor thereto.

The other blank 3^c will be laid upon the top face of the stack and its extremity 5^c,

projections 10^c and extensions 12^c can be bent over to engage the parts of the condenser stack in the same way as the first blank, the extremity 5^c and extensions 12^c engaging the lower face of the stack in Figs. 1 and 2. When finally in position, the extremity 5^b, for example, of the one blank or section will lie in the recess 7^a of the other blank, and the extensions 12^b of the same blank being bent over into engagement with the opposite face of the stack and in proximity to but separated from the edge of the body of the other blank by a narrow space or gap. These gaps between the end 5^b and extensions 12^b of the blank on the lower face of the condenser and the edges of the body of the blank 3^a on the upper face of the condenser, are indicated by the numerals 16 and 17, and similar spaces exist between the blank 3^b and the extremity and extensions of the other blank 3^c, on the lower face of the condenser. The two blanks, portions, or clamping members thus lie in such position that their corresponding long axes or lengths extend in substantially the same direction and are thus parallel with each other.

One-half of the conductive elements of the stack 1 may have projecting portions, indicated at 18, Fig. 2, at one end of the condenser, to be bent up and over upon the upper face of the condenser, for example, and clamped there-against under the section 3^a; and the complementary half of the conductive elements of the stack 1 can have similar projections to be bent down upon the same face of the condenser stack and clamped there-against by the end 5^b of the other blank; hence one section will be electrically united with one-half of the sheets of foil in the condenser, and the other section electrically united with the other half of the sheets of foil, while at the same time the two sections of the envelope 3^a and 3^b will be separated from one another at all points by the spaces 16 and 17 on both the opposite faces of the stack 1, these spaces providing just enough clearance to avoid impairing the efficiency of the condenser. The envelope thus not only encloses and protects the stack 1, but also greatly facilitates putting the condenser into circuit by the attachment of line wires to the projection 6^a and 6^b.

With an envelope of this nature completely enclosing the stack of the condenser, the stack is clamped and gripped tightly and firmly over its entire area, at all its corners and along all of its edges, to keep the conductive and dielectric elements in firm engagement and under the required degree of pressure, to prevent the separation of the conductive elements and the formation of air spaces inside of the condenser.

Thus the efficiency of the condenser is preserved and any impairment of structure or function prevented. Also, the danger of the condenser being broken or damaged at any point either at the corners or broken across at the middle is entirely obviated. I may further provide the projections 10^a and 10^b with extremities 19^a and 19^b, to be bent along transverse lines 20^a and 20^b, down upon the adjacent ends of the extensions 12^a and 12^b.

The envelope or casing for the condenser body can very easily be made by stamping out the blanks 3^a and 3^b, and very quickly attached to the stack 1 by bending. The jacket or casing adds very little to the cost of the article, and the increase in the strength and stiffness of the condenser, and the preservation of its efficiency and serviceableness will be appreciated by all those skilled in this art.

Having described my invention, what I believe to be new and desire to secure and protect by Letters Patent of the United

States is:—

1. A condenser comprising a stack having corners and edges connecting the corners, a casing for the stack comprising a pair of sections engaging opposite faces thereof, each section gripping the corners of the stack and the edges between the corners, the said sections being spaced from each other and each having attached thereto a terminal for said condenser.

2. A condenser comprising a stack having ends and edges connecting said ends, a member to engage a face of the stack, said member having a projection disposed adjacent one end of the stack to be attached to a circuit terminal and a recess disposed adjacent the other end of the stack, said member also having lateral extensions adjacent the recess to be bent over those edges of the condenser parallel with the length of said member.

3. A blank for a condenser casing, comprising a body having a projection at one end to be connected to a circuit terminal, a recess at the opposite end, projections from said opposite end flanking said recess, and extensions at the opposite sides adjacent said last-named projections, said extensions to be bent over the edges of the condenser.

4. A condenser comprising a stack and a member to engage one face of the stack, said member having an end folded over the adjacent end of the stack against the opposite face thereof, and a projection carried by said end folded over with said end upon the opposite face of the stack, and then back upon said end of said member parallel with the remainder of said member, to enable connection to be made with a circuit terminal.

5. A condenser comprising a stack having

corners and edges connecting said corners, and members engaging the stack and substantially covering the same at the corners and along the edges connecting said corners, the length of said members extending in 70 substantially the same direction, one of said members having attached thereto a terminal at one end of the condenser and the other member having attached thereto a terminal at the opposite end of the condenser, and 75 said members having portions bent over the opposite ends of the condenser at the corners thereof along a line transverse to said terminals.

6. A condenser comprising a stack having corners and edges connecting the corners, a casing for the stack comprising a pair of clamping members with their corresponding axes parallel engaging the opposite faces thereof, each member gripping adjacent 80 corners of the stack, and the edges between and adjacent said corners, said members being spaced from each other and each having attached thereto a terminal for the condenser.

7. A condenser comprising a stack and a casing for the stack, said casing comprising a portion engaging substantially the entire area of one face of the condenser and extending entirely across the same at one end, 85 said portion having parts bent over all the edges of the stack adjacent the corners at said end and over the edge of the condenser at the opposite end thereof, said portions being turned down against the other face of 90 the condenser, and another portion engaging substantially the entire area of the opposite face and extending entirely across said face at the opposite end of the condenser, said portion having parts bent over all the edges 95 of the condenser at the corners adjacent said opposite end and also across the edge at the first-mentioned end of the condenser and being turned down against the first face, the two portions being electrically separated 100 from each other.

8. A condenser comprising a stack including elements of conductive material separated by insulation, sections to cover the outside of the stack, the sections extending entirely across the width of the condenser at opposite ends thereof, each section engaging an exterior face of the stack and having portions to be bent over the opposite sides of the stack and turned down 110 into engagement with the other face thereof, the adjacent edges of the sections on the stack being separated from each other by a relatively small distance, each section having attached thereto a portion for enabling it to 115 be connected to an electric circuit, said portions being disposed at opposite ends of the condenser.

9. A condenser comprising a stack having corners and edges connecting the corners and 120

members engaging the stack and substantially covering the same at the corners, and along the edges, connecting said corners, one of said members having attached thereto

5 one of the terminals of the condenser and the other member having attached thereto the remaining terminal, and said members

each having portions bent over the opposite edges of the condenser adjacent the corners thereof and parallel to a line connecting 10 said terminals of the condenser.

In testimony whereof I affix my signature.

WILLIAM DUBILLIER.
